UNITED STATES PATENT OFFICE.

IREDELL HILLIARD, OF GEORGETOWN, SOUTH CAROLINA.

PAPER-FILE.

1,064,646.

Specification of Letters Patent. Patented June 10, 1913.

Application filed July 20, 1912. Serial No. 710,573.

To all whom it may concern:

Be it known that I, IREDELL HILLIARD, a citizen of the United States, residing at Georgetown, in county of Georgetown and State of South Carolina, have invented certain new and useful Improvements in Paper-Files, of which the following is a specification.

My invention relates to an improvement in paper files and has to do with that type of file in which a pin is supported and held by a frame upon a desk against the wall or at any convenient point so that letters, bills or other papers may be impaled upon the pin and held in position to be readily accessible.

The object of this invention is to provide a file in which a bifurcated keeper is so pivoted to a portion of the frame that the pin comes within the bifurcated portion and the keeper may be swung in a vertical plane either upwardly or downwardly.

A further object is in the provision of a pin which may be folded over upon the frame and form a flat structure which is more readily and conveniently packed for shipment or may be inserted in the pocket to be carried from place to place.

This invention consists of certain novel features of construction and combinations of parts which will be hereinafter more fully described and pointed out in the claims.

In the accompanying drawings Figure 1 is a view in perspective of the preferred form of my invention; Fig. 2 is a view in side elevation of the form disclosed in Fig. 1; Figs. 3 and 4 are perspective views showing other forms which my invention may take.

Referring to Figs. 1 and 2, a base or frame A, which is preferably formed of a single piece of sheet metal, has stamped from the body portion thereof feet 1 and 2 which are bent rearwardly for a short distance and then parallel with the body portion to rest against the wall or surface to which the file is to be attached and the foot 1 has an opening in which a screw 4 is received for attaching the file to the supporting surface. Near the bottom of the base A and on the forward side thereof, bearings 4', 4' are struck up, and in these bearings the pin 5, which in this instance is shown as being of the hook form, has its shank 6 mounted to have endwise movement. On

the extreme lower edge of the base A a strip 7 of the metal is left and this strip 7 extends forwardly for a short distance and then parallel with the base, as at 8. That portion of the strip 7 which is at right angles to the base, is adapted to support the pin and a slot 9 is formed in the parallel portion in which the pin is received and held against side swinging movement. When it is desired to fold the pin so that it will be flat against the base, the shank 6 is moved upwardly through the bearings 4, which causes the pin to travel out of the slot 9 and it can then be swung to the one side or the other against the base A. On the upper portion of the base A two tongues 10, 10 are bent forwardly, rearwardly and thence downwardly to form annular bearings, and the metal between these bearings is cut away both above and below. A keeper made in the form of a bell crank has arms 11 and 12 and at the point of juncture between the two arms bearing pins 13, 13 are provided which extend parallel with the angle of connection between the two arms. The bearing pins 13 are adapted to be received in the bearings 10 and the keeper swings in the cut away portion between these bearings. The arm 11 of the keeper is made preferably slightly longer than the distance between the pin 5 and the base A and has its outer end enlarged at 14 and the enlarged portion 14 of the arm 11 of the keeper is bifurcated at 15 for a sufficient length that the keeper has free pivotal movement in the bearings 10 when the pin 5 is in the bifurcated portion of the keeper. It is intended that the arm 11 of the keeper shall normally be in a horizontal plane or approximately at right angles to the upward extent of the pin 5, and as a means of retaining it in its normal position a spring 16 is connected through an opening 17 in the arm 12 and at 18 to the base or frame A. In the form of device shown in Fig. 3, the object and the results to be accomplished are the same as with the structure shown in Figs. 1 and 2, and in this view the base or frame A' and the pin 5' are disclosed as formed from a single length of wire and are readily connected together. The keeper has the arms 11' and 12' formed from a single length of wire and is pivoted in bends formed in the base wires A'. The keeper in this instance is resiliently retained in a horizontal position by the spring 16'.

The form of file disclosed in Fig. 4 is intended for use on a desk, table or similar article to be placed flat upon the top thereof. In this structure the base or frame A² has an arm 20 connected therewith, and extending approximately parallel with the pin 21 which is pivoted and has sliding movement in a bearing 22 struck up from the base A², and the pin is held in an upright position by being moved into the slot 23 formed in the strip 24 bent up from the base. The keeper has the arms 11² and 12² and spring 16² as disclosed in Fig. 1, and is in position to have the pin received in the bifurcated portion 15² on the arm 12².

It will thus be seen that I have provided a file with which the papers may be forced down over the pin moving the arm of the keeper before them and when they have passed beyond the path in which the arm swings, it is again returned to its normal position by the spring which is sufficiently strong to prevent the papers from becoming displaced from the pin due to being fanned by the wind or agitated in any other manner, and when it is desired to remove the papers from the file they are drawn upwardly over the pin, forcing the arm of the keeper aside and are taken off from the pin at the point. After the papers to be removed have passed beyond the path of the keeper arm, the spring again restores said arm to its normal position.

Having thus described my invention, what I claim as new and desire to secure by Letters Patent is—

1. A paper file comprising a frame, a pin connected with the frame upon which the papers are impaled, a keeper, having its end bifurcated, pivotally mounted in such position that the pin comes within the bifurcated portion, the keeper so pivoted to the frame that it has movement in a vertical plane downwardly and upwardly from the horizontal, and a spring for resiliently holding the keeper in position approximately at right angles to the pin.

2. A paper file comprising a frame, a bell crank keeper having one of its arms bi-

furcated, a pivotal connection between the keeper and frame approximately at the angle of juncture between the two arms of the keeper, a pin connected with the frame and extending upwardly into the bifurcated portion of the keeper in such a manner that the bifurcated arm has free pivotal movement downwardly and upwardly, and a spring connected to the free arm and to the frame for holding the bifurcated arm of the keeper in position approximately at right angles to the pin.

3. A paper file comprising a frame, a bearing struck up from the lower portion of the frame, a pin mounted to have sliding and pivotal movement in said bearing, a bent up portion adjacent the bearing having a groove formed therein in which the pin is held when in an operative position and from which it is disengaged by sliding through the bearing so that it may be swung flat against the frame, and a keeper pivoted near the upper portion of the frame to lie in a normal position approximately at right angles to the pin and to be swung downwardly as the papers are placed upon the pin and upwardly as they are removed.

4. A paper file comprising a frame, a pin pivotally connected to the frame to be swung flat against the frame for packing, means for holding the pin in its operative position separated from and approximately parallel with a portion of the frame, a bell crank keeper having one of its arms bifurcated to receive the pin, bearings formed on the upper portion of the frame, bearing pins formed on the keeper adjacent the angle of juncture between the arms thereof, and received in the bearings, and a spring connected to the free arm of the keeper and with the frame for holding the bifurcated arm in a position to retain the papers on the pin.

In testimony whereof I affix my signature, in the presence of two witnesses.

IREDELL HILLIARD.
